DUPLICATING APPARATUS

Hubert Jagger, Maywood, Ill., assignor to Ditto,
Incorporated, Chicago, Ill., a corporation of
West Virginia

Application May 13, 1940, Serial No. 334,851

17 Claims. (Cl. 101—133)

This invention relates to duplicating machines of the hectograph type and particularly to the type of machine as shown in my Letters Patent No. 2,188,599, dated January 30, 1940, which is provided especially for use with pay roll work for transferring the data from the master sheet either to a series of copy sheets in the form of pay checks or to a series of copy sheets in the form of individual yearly record cards. It is the principal object of the invention to improve machines of this type with respect to the means for supporting and positioning copy sheets for the transfer thereto of a selected portion of the subject matter carried by the gelatin master sheet, and for insuring that the copy sheets shall be in the required position for causing the printing to take place at the selected point on the copy sheet.

In machines of this type, a carriage is provided having a table or tray thereon for supporting a series of copy sheets of the record card type independently of the means for supporting pay checks or the like, together with means for giving the carriage a step by step movement with respect to the gelatin master sheet so that successive lines of the subject matter on the master sheet shall be printed by successive operations of the machine on the several copy sheets placed on the tray one at a time. In many cases, the copy sheets are provided with a plurality of lines at any one of which the printing may be effected under the control of adjustable margin means carried by the table or tray. For example, pay roll subject matter for any particular week carried by the master sheet may be copied on the individual record cards of the different workers, the data for all of the workers being printed on correspondingly numbered lines of the several copy sheets or cards.

In the arrangement shown, the means for giving the carriage a step by step movement corresponds substantially to the construction shown by said prior Letters Patent, but a new and improved form and arrangement of parts is provided for controlling the positioning of the copy sheets on the carriage. This means comprises a margin bar positioned transversely of the table or tray and mounted so as to be capable of being readily and quickly adjusted on the carriage longitudinally of the machine. In the preferred arrangement, the margin bar is positioned so as to rest on the tray and to be slidable along the face of the tray, and the means for holding the margin bar in adjusted position longitudinally of the machine is arranged in the form of a clutch adapted to resist movement of the margin

bar from its successive normal stop positions while being at the same time adapted to yield readily for adjustment from one stop position to another upon the application of pressure thereto for the purpose of effecting an adjustment.

The improved arrangement comprises also margin stop devices adjustable on the margin bar transversely of the machine so as to be available for convenient use for adjusting the copy sheets 10 transversely of the gelatin master sheet. In the preferred arrangement, two of such margin stop devices are provided, one at each side of the machine, arranged so as to be available for use alternatively for engagement with one or the other side edge of the copy sheet.

The improved apparatus comprises further improved means for connecting the front portion of the table or tray with the body portion thereof so as to enable such front portion to be very 20 quickly and easily removed when desired.

It is another object of the invention to improve machines of this type in sundry details hereinafter pointed out. The preferred means by which the several objects have been attained are 25 illustrated in the accompanying drawings, in which—

Fig. 1 is a top plan view of the preferred form of the improved machine;

Fig. 2 is a side face view of the machine of 30 Fig. 1;

Fig. 3 is a front face view of a fragmentary portion of the carriage of the machine;

Fig. 4 is a vertical sectional view taken substantially at the line 4—4 of Fig. 2;

Fig. 5 is a vertical sectional view taken substantially at the line 5—5 of Fig. 1;

Fig. 6 is a view similar to Fig. 5 but showing a changed position of some of the parts;

Fig. 7 is a diagrammatic view showing on an 40 enlarged scale certain of the framework and operating parts as seen in Fig. 2, with some of the parts broken away and with other parts omitted;

Fig. 8 is a top plan view of the table or tray 45 disengaged from the carriage upon which it is normally mounted;

Fig. 9 is a top plan view of one corner of the front portion of the table or tray shown on a considerably enlarged scale as compared with Fig. 1;

Fig. 10 is a vertical sectional view taken substantially at the line 10—10 of Fig. 11;

Fig. 11 is a top plan view corresponding to the showing of Fig. 9 but showing in connection therewith a corner of the body portion of the table or tray;

Figs. 12 and 13 are vertical sectional views taken on an enlarged scale at the line 12-12 and the line 13-13, respectively, of Fig. 1;

Figs. 14, 15 and 16 are vertical sectional views taken at the line 14-14, the line 15-15, and the line 16-16, respectively, in Fig. 12;

Fig. 17 is a vertical sectional view taken substantially at the line 17-17 of Fig. 16; and

Fig. 18 is a view similar to Fig. 17 but showing a changed position of the parts.

Referring now to Figs. 1 to 7 inclusive, the machine comprises a frame 25 supported from a cabinet 26. In the arrangement shown, the frame at each side of the machine comprises two frame bars 27 and 28 having a longitudinally extending slot 29 between the bars at each side of the machine. Underneath the bars 27, there is provided a transversely extending frame member 30 which has upwardly extending arm portions 31 at its ends in slightly spaced relation to the side faces of the frame bars 27, as is clearly shown in Fig. 4, only one end portion of the frame bar 30 being shown. Upon the upper ends of the arms 31, I have provided a transverse frame member 32, the frame members 30, 31 and 32 constituting the principal carrying parts which are adapted to be moved back and forth along the frame 25, such parts constituting the framework of the carriage of the machine.

The means for mounting the carriage movably upon the frame 25 comprises a bar 33 mounted longitudinally of the carriage at each side thereof, such bar being held by means of bearing balls 34 in anti-friction relationship with a channel bar 35 carried by the frame member 27 at each side of the machine.

Between the frame bars 27, there is mounted a bed plate 36 of any approved form over which a duplicating pad or band 37 is stretched, such duplicating pad being preferably of the type having a gelatinized face so as to be capable of receiving the ink from a master sheet applied thereto. In machines of this type heretofore in use, means have been provided for holding the duplicating pad 37 in operative position and for shifting it as may be desired with respect to the bed. Inasmuch as this holding and adjusting means forms in and of itself no part of the present invention, it is believed to be unnecessary to describe it further in detail.

Upon the frame plate 32, there is mounted a housing 38 of any approved form extending across the machine from one side to the other, as is clearly shown in Fig. 1. Within the housing 38, there is mounted a platen roller 39 so as to be free to rotate and so as to be movable vertically toward and from the duplicating pad 37. In the arrangement shown, the platen roller 39 is mounted by means of a shaft 40 journaled at its ends in the arms of a yoke 41 which is pivotally mounted upon a shaft 42 journaled at its ends in the end walls of the housing 38. For turning the shaft 42 so as to swing the yoke 41 and the platen roller 39 vertically toward and from the duplicating pad, a handle 43 is mounted upon the shaft at an intermediate point therealong, such handle being provided with a forwardly extending lug 44 thereon (see Fig. 5). The arrangement is such that when the lever or handle 43 is standing in its normal position as shown in Fig. 5 the platen roller 39 is held in raised position, the roller 39 being given an operative stroke downwardly toward the duplicating pad upon a backward stroke of the handle 43 into the position as shown in Fig. 6.

Means is provided at the rear edge portion of the housing 38 for supporting a copy sheet such as a pay check, such means comprising an obliquely disposed tray or table 45 along which a copy sheet such as the sheet 46 as shown in Fig. 5 is slidable into engagement with a margin bar 47. In the arrangement shown, the margin bar 47 is movably mounted in position by means of brackets 48 which in turn are pivotally mounted upon pins or rivets 49 carried by the end walls of the housing 38 (see Fig. 6). Coiled springs 50 are connected at their rear ends with the brackets 48 and at their forward ends with the shaft 42, serving normally to hold the brackets in the position as shown in Fig. 5 with the margin bar 47 in substantial alignment with the tray 45 so as normally to engage the forward edge of a copy sheet 46 carried by the tray. The arms of the yoke 41 are provided with pins 51 in position to engage the brackets 48 upon downward movement of the yoke so as to swing the brackets and the margin bar 47 in clockwise direction from the position as shown in Fig. 5 to the position as shown in Fig. 6 against the action of the springs 50 when the handle 43 is moved backwardly to the position as shown in said Fig. 6. A spring 52 is provided upon the shaft 42 so as to engage the yoke 41 serving normally to hold the lever or handle 43 in substantially vertical position as shown in Fig. 5, with the platen roller 39 in raised position. A pressure roller 53 is journaled in position adjacent to the platen roller 39 so as to be adapted by cooperation with the platen roller to grip a copy sheet such as the sheet 46 when pushed downwardly by the platen roller as shown in Fig. 6.

Upon the front face of the housing 38, a transversely extending lever 54 is pivotally mounted by means of a bolt 55 (see Fig. 3), such lever 54 having its inner end positioned underneath the lug 44 carried by the handle or lever 43. The arrangement is such that upon forward movement of the lever 43 from the position as shown in Fig. 6 to the normal position as shown in Fig. 5, the lever 54 is swung in counter clockwise direction in Fig. 3 for raising the outer end of said lever 54 so as to effect a movement of associated means as hereinafter described.

Means is provided for giving the carriage a step by step movement toward the right in Figs. 2 and 7, comprising a pair of levers 56 and 57 which have releasable engagement with a rack bar 58 carried by the frame 25. The lever 56, as is best shown in Fig. 7, is pivotally connected by means of a pin or rivet 59 at an intermediate point with a bellcrank lever 60 which is pivotally mounted upon a pin or bolt 61 carried by a longitudinally extending bar 62 mounted upon the frame bar 31 by means of machine screws 63 and 64. At the forward end of the forwardly extending arm of the bellcrank lever 60, two lugs 65 and 66 are provided in vertically spaced relation to each other.

Upon the pin or bolt 61 (see Fig. 4) adjacent to the bellcrank lever 60, there are provided two short arms or levers 69 and 70 with a ratchet wheel 71 mounted therebetween, all of such parts being loosely mounted upon said bolt 61. Between the free forward ends of the levers 69 and 70, there is mounted a pawl 72 having its rear end in engagement with the ratchet wheel 71 so that upon movement of the arms or levers 69 and 70 in clockwise direction in Fig. 7 the ratchet wheel is given a corresponding rotary movement. A second pawl 73 is likewise mounted so

as to engage the ratchet wheel 71, such pawl 73 being pivotally mounted upon the arm 31 of the frame member 30. The pawl 73 normally is supported in full operative engagement with the ratchet wheel 71 by means of an arm 74 rising from the lever 57. The lever 57 is pivotally mounted by means of a bolt 75 upon a bracket 16 carried by the frame arm 31.

In the arrangement shown, the lever 79 is connected by a coiled spring 77 with an arm 78 carried by the bracket 76 so as normally to hold the levers 69 and 70 in lowered position in engagement with the lug 65 of the bellcrank lever 60. The rear end of the lever 57 is connected by means of a spring 79 with the machine screws 64 directly above so as to hold the lever 57 normally turned to the limit of its movement in counterclockwise direction in Fig. 7. A spring 80 connected between the downwardly extending arm of the bellcrank lever 60 and a suitable portion of the framework serves normally to hold the bellcrank lever turned to the limit of its movement in counterclockwise direction in said Fig. 7. A flat spring 81 carried by the bracket 76 and bearing on the lever 56 normally holds such lever 56 turned to the limit of its motion in counterclockwise direction in said Fig. 7.

As is clearly shown in Figs. 2 and 7, the rack bar 58 is provided with a plurality of substantially square notches 82 arranged in spaced relation to each other therealong, together with a substantially V-shaped notch 83 in its forward end. For convenience of reference thereto, the first two of the square notches at the forward end of the bar 58 are designated as 82a and 82b respectively, in said Fig. 7. The forward end portions of the levers 56 and 57 are turned downwardly to provide arms or lugs 84 and 65 thereon, the lug 84 being shaped to conform to the shape of the notch 83. The lower end portion of the lug 85 of the lever 57 is turned into horizontal position so as to provide an engaging portion 86 in position to engage one or another of the notches 82 in the rack bar 58.

With the parts in the arrangement as shown in Fig. 5 with the handle or lever 43 in its normal substantially upright position, and with the lug 86 of the lever 57 engaging the notch 82a of the rack bar 58, the lever 54 will be standing with its inner end depressed and its outer end raised so as to hold the arms 69 and 70 in their uppermost position, such arms in this position serving by engagement with the lug 66 on the bellcrank lever 60 to hold the lever 60 swung backwardly to the limit of its motion above the pivot pin 59. In this position of the parts, the lug 84 of the lever 56 will be standing in engagement with the top face of the rack bar 58 at the left of the notch 83.

Under these conditions a copy sheet 46 will be placed face downwardly upon the obliquely disposed supporting tray 45 and will be moved downwardly into engagement with the margin bar 47, whereupon the machine is ready for an operative stroke of the handle or lever 43 backwardly for printing data from the duplicating pad 37 upon the copy sheet. Upon the initial movement of the lever 43 backwardly, the lever 54 is swung in clockwise direction in Fig. 3 for permitting the spring 77 to swing the arms 69 and 70 downwardly and to swing the bellcrank lever 60 in counterclockwise direction in Fig. 7 for carrying the lever 56 into position for permitting the lug 84 to engage the notch 83 of the rack bar 58 under the influence of the flat spring 81. Up-

on the continued movement of the lever 43 backwardly, the platen roller 39 is brought into operative engagement with the copy sheet 46 which is pressed downwardly by the platen roller into operative engagement with the duplicating pad 37 for a transfer of the first line of printing from the pad 37 to the copy sheet.

After the proper pressure has been applied upon the copy sheet 46, the lever 43 is again moved manually to its normal forward position. The arrangement of the parts is such that upon the upward movement of the platen roller 39 such roller cooperates with the pressure roller 53 for stripping the copy sheet from the gelatin pad 37. At the same time, the lug 44 by engagement with the lever 54 causes the outer end of said lever 54 to move upwardly for raising the arms 69 and 70 so as to give the pawl 72 an operative stroke for rotating the ratchet wheel 71 in clockwise direction in Fig. 7. This rotation of the ratchet wheel 71 serves to force the pawl 73 downwardly by a camming action thereon so as to press downwardly on the arm 74 carried by the lever 57 for causing such lever 57 to swing in clockwise direction in Fig. 7 out of engagement with the rack bar 58 against the action of the spring 79. As the upward swinging movement of the arms 69 and 70 continues, such arms are brought into engagement with the lug 66 carried by the bellcrank lever 60, after which the still further continued upward swinging of the arms causes the bellcrank lever to swing backwardly about the pivot pin 59 so as to carry the pin 61 and the carriage upon which such pin is mounted toward the right in Fig. 7 for bringing the lug 86 of the lever 57 into position directly above the notch 82b of the rack bar 58. The arrangement is such that at the time when the lug 86 comes opposite to said notch 82b in the rack bar, the ratchet wheel 71 in its rotary movement reaches such a position that the pawl 73 clears the engaged tooth of the ratchet wheel so as to permit the spring 79 to swing the lever 57 in counterclockwise direction in Fig. 7 for bringing the lug 86 into engagement with said notch 82b and for bringing the pawl 73 into engagement with the next adjacent tooth of the ratchet wheel.

At the end of the step of operation as above described, the handle or lever 43 will be again in substantially upright position, with the lever 57 engaging the notch 82b of the rack bar 58, and with the downwardly projecting lug 84 of the lever 56 engaging the notch 83, the bellcrank lever 60 being held then against a return swinging movement to the position as shown in Fig. 7 by the lever 54 which continues to hold the arms 69 and 70 at this time in their uppermost position. Upon the next subsequent stroke of the handle or lever 43 backwardly after the insertion of a new copy sheet upon the tray 45, the arms 69 and 70 are moved downwardly again by the spring 77 as above described, such spring 77 serving also to move the bellcrank lever 60 in counterclockwise direction about the pin 61 to the position as shown in said Fig. 7, such counterclockwise movement of the lever 60 serving to shift the lever 56 from its engagement with the notch 83 to engagement with the notch 82a.

As is clearly shown in Fig. 2, the frame bar 27 at the near side of the machine is provided with a forwardly projecting lug 87 which is held adjustably in position, in the arrangement shown, by a mechanism comprising a set screw 88. At the forward end of the machine, a bracket 69 is

provided, pivotally mounted upon a horizontal axis so as to be moved into and out of position in alignment with the lug 87, such bracket in the arrangement shown being in the form of an angle bar comprising a vertically extending arm by which the bracket is swingingly mounted in position and a longitudinally extending arm fixedly mounted on the end of the vertically disposed arm.

Upon the frame member 31 of the carriage, there is mounted an arm or lever 90 adapted to swing backwardly and forwardly about the transverse horizontal axis and provided with a pin 91 at its end extending transversely of the machine into position between the lug 87 and the bracket 89. The arrangement is such that, upon backward movement of the carriage toward the right in Fig. 2 to the limit of its movement, the pin 91 is brought into engagement with the lug 87 so as to swing the lever 90 toward the left in Fig. 2 into engagement with a stop pin 90a carried by the carriage frame member 31. In this movement of the lever 90, the pin 91 pushes downwardly on the levers 56 and 57 at their rear end portions so as to lift the forward ends of said levers out of engagement with the rack bar 58 against the action of the springs 81 and 79. Inasmuch as the lever 90 and the pin 91 in their movement toward the left in Fig. 2 by contact with the lug 87 as above described move into past-center position with respect to the axis of said lever 90, the levers 56 and 57 are of course retained in their inoperative position until such lever 90 is swung again toward the right into its normal position as shown in Fig. 7. The arrangement is such that, when the carriage is moved to the limit of its motion toward the left in said Fig. 7, with the bracket 89 in its operative raised position as shown in solid lines, the bracket 89 engages the pin 91 so as to swing the lever 90 again into its normal position as shown in Fig. 2.

When the carriage has been moved to the limit of its motion toward the left in Fig. 2 and has then been returned toward the right for starting a duplication operation, the lever 57 is held out of engagement with the V-shaped notch 83 but is permitted to drop into engagement with the first square notch 82a at the left so as to stop the backward movement of the carriage. Under these circumstances, the lever 56 stands in position with its lug 84 engaging the top face of the rack bar 58 at the left of the notch 83, the lever 56 being adapted to remain in this position until the bellcrank lever 60 is swung in counter clockwise direction in Fig. 7 into the position as there shown, which movement of the bellcrank lever takes place upon the next succeeding movement of the handle or lever 43 backwardly into the position as shown in Fig. 6. This movement is timed to occur at about the time when the platen roller 39 reaches its lowermost position.

It will be understood that the lever 90 may be moved manually, independently of the action of the lug 87 and the bracket 89, into its operative position in which it holds the levers 56 and 57 out of engagement with the rack bar 58. It will be understood also that when the lever 90 is in its forward operative position, with the bracket 89 swung downwardly out of its operative position, the carriage is then free to move back and forth to the limit of its motion in either direction so as to be capable then of being employed like any ordinary hectograph duplicating machine independently of any step by step for-

warding movement of the carriage. It will be understood further that with the bracket 89 swung upwardly into operative position, the carriage can be set at any desired operative position along the rack bar 58, this being effected by a manual manipulation of the levers 56 and 57 through the medium of the lever 90 and the pin 91.

In the machine as shown in the drawings, the carriage which is movable along the bed is provided with a tray or table member 92 in substantially horizontal position underneath the frame member 38, as is clearly shown in Fig. 5, for use in lieu of the tray 45 for supporting a copy sheet in the form of an individual record card, being provided with an opening 93 therethrough for the movement of the platen roller 38 into operative printing position as shown in Fig. 6. At its forward end, the tray member 92 is provided with an extension tray member 94 pivotally mounted in position upon the body member 92 of the tray by means of pivot pins 95 and 96 carried by the tray member 94 and extending into socket members 97 carried by the tray member 92. As is best shown in Figs. 9, 10 and 11, the tray member 94 is provided with a backwardly extending lug 98 adapted in the normal horizontal position of the tray member 94 to engage an opening 99 in the tray member 92. The arrangement is such that the two tray members 92 and 94 are held firmly in connection with each other so long as the front tray member 94 remains in its horizontal position, but such that when the tray member 94 is swung upwardly for carrying the lug 98 out of engagement with the opening 99 the extension tray member 94 can be moved sidewise out of engagement with the socket members 97 for effecting a separation of the extension member from the body member.

The tray member 92 in the arrangement shown is provided with supporting wheels 100 adapted by engagement with the frame members 27 to support the tray member in normal spaced relation to the bed 36. In like manner, the tray member 94 is provided with supporting wheels 101 in position normally to engage the frame members 27. At its side edges, the tray member 92 is provided with side margin bars 102 fixedly secured in position.

Margin bar means is provided for controlling the position of a copy sheet in the form of a record card upon the tray longitudinally of the machine with the card lying face down flat on the tray underneath the platen 30, being adjustably mounted in position upon the carriage of the machine by means of a longitudinally extending slide bar 103. As is clearly shown in Figs. 12 and 13, the forward end of the bar 103 is connected directly with the frame member 38 of the carriage, and the rear end of the slide bar is mounted in position by means of a bracket 104 extending rearwardly from the tray member 92. Immediately above the slide bar 103, there is a second bar 105 also connected directly with the frame bar 38 of the carriage, being supported at its rear end by a bracket 106 rigidly connected with the bracket 104.

In the arrangement shown, the rod or bar 103 is made adjustable with respect to the table or tray 92. For effecting this result, the rear end portion of the bar where it extends through the parts 104 and 106 is threaded, as shown in Fig. 13, being held in position by nuts 103a and 103b which are capable of adjustment along the bar

for changing its position longitudinally of the machine with respect to the tray.

As is best shown in Figs. 12 and 13, the slide bar 103 is provided with annular grooves 107 thereabout in suitable spaced relation along the bar. Upon the slide bar 103, a slide block 108 is adjustably mounted, said block being provided with a groove 109 in its upper face engaging the bar 105, as is best shown in Fig. 16, the bar 105 serving to hold the block 108 in its normal operative position as shown in said figure. The block 108 is provided with a handle 110 extending from its side face for expediting movement of the block along the bars 103 and 105.

As is clearly shown in Figs. 16 and 17, the block 108 is provided at its bottom face with a deep groove 111 which provides a recess about the rod 103 for the reception of a clutch device 112. In the arrangement shown, the clutch device 112 is in the form of an elastic ring made from a length of coiled spring, the ring being of such size that it is adapted to grip the reduced portions of the rod or bar 103 at the grooves 107, as is shown in Fig. 17. The arrangement is such however that when the block 108 is moved along the rod 103 toward the right into the position as shown in Fig. 18, for example, the elastic band or ring 112 expands for permitting such movement. The arrangement is such that with the parts in the position as shown in Fig. 17 the clutch member 112 holds the block 108 in predetermined normal adjustment with respect to the bar 103, with the ring 112 centered in the groove 107. While the clutch member is effective for holding the block 108 normally in adjusted position, the block is readily movable along the bar upon the application of pressure upon the handle 110 for effecting an adjustment. The bar 105 is provided on its top face with a strip 113 which is graduated to correspond to the spacing of the grooves 107 in the bar 103 serving to indicate at any time the adjusted position of the block 108 longitudinally of the machine.

As is best shown in Figs. 12 and 16, a forwardly extending arm 114 is pivotally mounted upon the block 108 by means of upwardly turned ear portions 115, such arm at its forward end being provided with a transversely positioned margin bar member 116 rigidly mounted on the arm for engaging the end of a record card as shown in Fig. 8. The margin bar 116 is preferably formed of sheet metal in the form of an angle comprising a vertically positioned portion resting upon the tray or table 92, the forward edge portion of the bar being obliquely positioned as shown at 117 for expediting the movement of a copy sheet into effective engagement with the bar. In the construction illustrated, the tray 92 is provided with upwardly open grooves 118 extending longitudinally of the machine, the margin bar 116 being provided with downwardly extending lugs 119 in position to engage the grooves so as to prevent a copy sheet from slipping between the margin bar and the table or tray.

At opposite sides of the machine, stop devices are mounted upon the margin bar 116 so as to be adjustable transversely of the machine on the bar. Each of these stop devices is in the form of a piece of sheet metal 120 held in position on the margin bar by means of a rivet 121 extending through said sheet metal piece and through a slot 122 in the end portion of the margin bar, as is best shown in Fig. 8. The connection of the rivet 121 with the sheet metal plate 120 is reinforced by means of a block 123 which is provided

with pins 124 which extend upwardly through the slot 122 for assisting in holding the device in operative position. At its forward end, the sheet metal member 120 is provided with downwardly turned flanges 125 which serve as side margin stops for controlling the position of a card on the table transversely of the table, as is indicated in Fig. 8. The slots 122 are open at their outer ends, as is clearly shown in Fig. 8, so as to permit the stop devices 123 to be slid readily out of engagement with the margin bar 116 if desired.

From the above description, it will be appreciated that this improved machine is adapted to operate in three different manners. With the bracket 89 in lowered position, the machine operates for general use independently of system work. With the bracket 89 raised, the machine is in condition for either of two types of system operation. A weekly pay roll having been produced on the gelatin pad, showing the work of 26 workers, for example, the required 26 pay checks can be printed as above described by the use of the tray 46. Thereafter, the stop 116 may be set at the desired point longitudinally of the tray 92, as indicated by the scale on the bar 113 for copying the pay roll subject matter on the individual record cards of the workers involved. If the pay roll is the first of a new fiscal year, the stop 116 would be set at the No. 1 position as indicated by the scale. The carriage is then set at the starting position as indicated by the scale on the frame bar 27 at the far side of the machine, as shown in Fig. 1, and the individual record cards of the several workers are presented one at a time at the successive step positions of the carriage, each card being placed in turn flat on the tray 92 with its end squarely against the margin bar 116. Each card in turn is pressed against the appropriate line of the gelatin pad by the platen 39 under the control of the lever or handle 43, the carriage being given a step movement between each two successive impression operations. With the cards of the several workers presented in the same order as that in which the names appear, the data relating to each worker on the pay roll is copied on that worker's record card at the desired point thereon.

By the use of the improved arrangement, I am enabled to bring the margin bar 116 very easily into the desired adjusted position for insuring that the point at which the copy sheet is pressed into printing relationship shall correspond with the positions of successive lines of subject matter on the duplicating pad. This result is effected by an adjustment of the rod 103 longitudinally of the carriage by means of the nuts 103a and 103b.

By the use of the improved construction as above described, I am enabled very quickly and easily to adjust the margin bar 116 with respect to the carriage of the duplicating machine for controlling the point on a copy sheet at which a printing operation shall be carried out as set forth above. By the provision of the improved construction, the availability of the machine for varied use is substantially improved.

While the form and arrangement of parts as above described are preferred, it is to be understood that the invention is not limited to the arrangement illustrated except so far as the claims may be so limited, it being clear that changes might well be made in the construction without departing from the invention.

I claim:

1. A flat bed duplicating machine, comprising

in combination a frame, a bed mounted on said frame and provided with means for holding a duplicating pad in position thereon, a carriage movable along said bed longitudinally of the machine, a tray on said carriage for supporting a copy sheet, means for forcing the copy sheet at a predetermined point on the tray into printing relationship with said duplicating pad, a margin bar movably mounted on said carriage in transverse position thereon so as to be adjustable on the carriage longitudinally of the machine, releasable holding means adapted normally to hold the margin bar at any of a series of successive stop positions but adapted to yield for adjustment of the margin bar from one stop position to another, and means for giving said carriage successive step movements along the bed for bringing copy sheets into printing relationship with different portions of the duplicating pad.

2. A flat bed duplicating machine, comprising in combination a frame, a bed mounted on said frame and provided with means for holding a duplicating pad in position thereon, a carriage movable along said bed longitudinally of the machine, a tray on said carriage for supporting a copy sheet, means for forcing the copy sheet at a predetermined point on the tray into printing relationship with said duplicating pad, a slide bar mounted on said carriage longitudinally thereof a short distance above said tray at about the middle of the machine transversely thereof, a margin bar slidably mounted on said slide bar so as to be held in transverse position a short distance above said tray in any desired adjustment longitudinally of the machine, adjustable means for holding said margin bar releasably in position on said slide bar at any of a series of successive stop positions in predetermined step relation to each other, and means for giving said carriage successive step movements along said bed for bringing copy sheets into printing relationship with different portions of the duplicating pad.

3. A flat bed duplicating machine, comprising in combination a frame, a bed mounted on said frame and provided with means for holding a duplicating pad in position thereon, a carriage movable along said bed longitudinally of the machine, a tray on said carriage for supporting a copy sheet, means for forcing the copy sheet at a predetermined point on the tray into printing relationship with said duplicating pad, a slide bar mounted on said carriage longitudinally thereof a short distance above said tray, a slide block adjustably mounted on said slide bar, a margin bar movably connected with said slide block so as to rest on said tray in transverse position thereon, adjustable means for holding said slide block releasably in position on said bar at any of a series of successive stop positions therealong, and means for giving said carriage successive step movements along said bed for bringing copy sheets into printing relationship with different portions of the duplicating pad.

4. A flat bed duplicating machine, comprising in combination a frame, a bed mounted on said frame and provided with means for holding a duplicating pad in position thereon, a carriage movable along said bed longitudinally of the machine, a tray on said carriage for supporting a copy sheet, means for forcing the copy sheet at a predetermined point on the tray into printing relationship with said duplicating pad, a slide bar mounted on said carriage longitudinally thereof a short distance above said tray, a slide

block adjustably mounted on said slide bar, an arm pivotally mounted on a transverse axis of said slide block, a margin bar connected with said arm so as to rest on said tray in transverse position thereon, adjustable means for holding said slide block releasably in position on said slide bar at any of a series of successive stop positions therealong, and means for giving said carriage successive step movements along said bed for bringing copy sheets into printing relationship with different portions of the duplicating pad.

5. A flat bed duplicating machine, comprising in combination a frame, a bed mounted on said frame and provided with means for holding a duplicating pad in position thereon, a carriage movable along said bed longitudinally of the machine, a tray on said carriage for supporting a copy sheet, means for forcing the copy sheet at a predetermined point on the tray into printing relationship with said duplicating pad, a margin bar movably mounted on said carriage in transverse position thereon so as to rest on said tray and so as to be adjustable on the carriage longitudinally of the machine, tongue and groove connections between said tray and said margin bar for making the margin bar effective for stopping the edge of a sheet pressed thereagainst, releasable holding means adapted normally to hold the margin bar at any of a series of successive stop positions along the tray, and means for giving said carriage successive step movements along the bed for bringing copy sheets into printing relationship with different portions of the duplicating pad.

6. A flat bed duplicating machine, comprising in combination a frame, a bed mounted on said frame and provided with means for holding a duplicating pad in position thereon, a carriage movable along said bed longitudinally of the machine, a tray on said carriage for supporting a copy sheet, means for forcing the copy sheet at a predetermined point on the tray into printing relationship with said duplicating pad, a slide bar mounted on said carriage longitudinally thereof a short distance above said tray at about the middle of the machine transversely thereof, a slide block adjustably mounted on said slide bar, an arm pivotally mounted on a transverse axis on said slide block, a margin bar connected with said arm so as to rest on said tray in transverse position thereon, upwardly open grooves in said tray longitudinally of the machine, lugs on said margin bar adapted to traverse said grooves as said margin bar is adjusted with said slide block so as to be effective for stopping the edge of a sheet pressed against the margin bar, adjustable means for holding said slide block releasably in position on said slide bar at any of a series of successive stop positions along the slide bar, and means for giving said carriage successive step movements along said bed for bringing copy sheets into printing relationship with different portions of the duplicating pad.

7. A flat bed duplicating machine, comprising in combination a frame, a bed mounted on said frame and provided with means for holding a duplicating pad in position thereon, a carriage movable along said bed longitudinally of the machine, a tray on said carriage for supporting a copy sheet, means for forcing the copy sheet at a predetermined point on the tray into printing relationship with said duplicating pad, a slide bar mounted on said carriage longitudinally thereof a short distance above said tray, a slide

block adjustably mounted on said slide bar, a margin bar movably connected with said slide block so as to rest on said tray in transverse position thereon, releasable holding means adapted normally to hold said slide block at any of a series of successive stop positions along the slide bar but adapted to yield for adjustment of the margin bar from one stop position to another, means for adjusting said slide bar longitudinally with respect to said carriage, and means for giving said carriage successive step movements along said bar for bringing copy sheets into printing relationship with different portions of the duplicating pad.

8. A flat bed duplicating machine, comprising in combination a frame, a bed mounted on said frame and provided with means for holding a duplicating pad in position thereon, a carriage movable along said bed longitudinally of the machine, a tray on said carriage for supporting a copy sheet, means for forcing the copy sheet at a predetermined point on the tray into printing relationship with said duplicating pad, a slide bar mounted on said carriage longitudinally thereof a short distance above said tray and having a series of successive notches therein in spaced relation to each other along the bar, a margin bar slidably mounted on said slide bar so as to be held in transverse position a short distance above said tray in any desired adjustment longitudinally of the machine, coiled spring means connected with said margin bar adapted by yielding engagement with the notches in said slide bar normally to hold said margin bar releasably in adjusted position along said slide bar, and means for giving said carriage successive step movements along said bed for bringing copy sheets into printing relationship with different portions of the duplicating pad.

9. A flat bed duplicating machine, comprising in combination a frame, a bed mounted on said frame and provided with means for holding a duplicating pad in position thereon, a carriage movable along said bed longitudinally of the machine, a tray on said carriage for supporting a copy sheet, means for forcing the copy sheet at a predetermined point on the tray into printing relationship with said duplicating pad, a rod mounted on said carriage longitudinally thereof a short distance above said tray and having a series of annular grooves thereabout in spaced relation to each other along the rod, a slide block slidably mounted on said rod and having a recess therein about the rod, an elastic ring on said rod in said recess adapted normally by engagement with one of said grooves to hold the slide block in predetermined adjusted position on the rod but adapted to expand for movement from one groove to the next, a margin bar connected with said slide block so as to be held in transverse position on said tray, and means for giving said carriage successive step movements along said bed for bringing copy sheets into printing relationship with different portions of the duplicating pad.

10. A flat bed duplicating machine, comprising in combination a frame, a bed mounted on said frame and provided with means for holding a duplicating pad in position thereon, a carriage movable along said bed longitudinally of the machine, a tray on said carriage for supporting a copy sheet, means for forcing copy sheet at a predetermined point on the tray into printing relationship with said duplicating pad, a rod mounted on said carriage longitudinally thereof

75 a short distance above said tray and having a series of annular grooves thereabout in spaced relation to each other along the rod, a slide block slidably mounted on said rod and having a recess therein about the rod, an elastic ring on said rod in said recess adapted normally by engagement with one of said grooves to hold the slide block in predetermined adjusted position of the rod but adapted to expand for movement from one groove to the next, an arm pivotally mounted on a transverse axis on said slide block, a margin bar connected with said arm so as to rest on said tray in transverse position thereon, upwardly open grooves in said tray longitudinally of the machine, lugs on said margin bar adapted to traverse said grooves as said margin bar is adjusted so as to be effective for stopping the edge of a sheet pressed against the margin bar, and means for giving said carriage successive step movements along said bed for bringing copy sheets into printing relationship with different portions of the duplicating pad.

11. A flat bed duplicating machine, comprising in combination a frame, a bed mounted on said frame and provided with means for holding a duplicating pad in position thereon, a carriage movable along said bed longitudinally of the machine, a tray on said carriage for supporting a copy sheet, means for forcing the copy sheet at a predetermined point on the tray into printing relationship with said duplicating pad, a rod mounted on said carriage longitudinally of the machine a short distance above said tray and having a series of annular grooves thereabout in spaced relation along the rod, a slide block slidably mounted on said rod, a clutch member in the form of an elastic ring mounted on said rod and of a size for gripping the reduced portions of the rod at said grooves and connected with 25 said slide block so as normally to hold the block in adjusted position on the rod but adapted to expand for movement from one groove to the next, a margin bar connected with said slide block so as to be held in transverse position on said tray, and means for giving said carriage successive step movements along said bed for bringing copy sheets into printing relationship with different portions of the duplicating pad.

12. A flat bed duplicating machine, comprising in combination a frame, a bed mounted on said frame and provided with means for holding a duplicating pad in position thereon, a carriage movable along said bed longitudinally of the machine, a tray on said carriage for supporting a copy sheet, means for forcing the copy sheet at a predetermined point on the tray into printing relationship with said duplicating pad, a rod mounted on said carriage longitudinally of the machine a short distance above said tray and having a series of annular grooves thereabout in spaced relation along the rod, a slide block slidably mounted on said rod, an endless band clutch member in the form of a coiled spring mounted on said rod and engaging said slide block for holding the block in adjusted position on the rod by a gripping engagement with the reduced portions of the rod at said grooves but adapted to expand for movement out of engagement with a groove, a margin bar connected with said slide block so as to be held in transverse position on said tray, and means for giving said carriage successive step movements along said bed for bringing copy sheets into printing relationship with different portions of the duplicating pad.

13. A flat bed duplicating machine, comprising in combination a frame, a bed mounted on said frame and provided with means for holding a duplicating pad in position thereon, a carriage movable along said bed longitudinally of the machine, a tray on said carriage for supporting a copy sheet, means for forcing the copy sheet at a predetermined point on the tray into printing relationship with said duplicating pad, a slide bar mounted on said carriage longitudinally thereof a short distance above said tray, a slide block adjustably mounted on said slide bar, an arm pivotally mounted on a transverse axis of said slide block, a margin bar connected with said arm so as to rest on said tray in transverse position thereon, adjustable means for holding said slide block releasably in position on said slide bar at any of a series of successive stop positions along the bar, graduated means on said carriage for showing the adjustment of said margin bar thereon, and means for giving said carriage successive step movements along said bed for bringing copy sheets into printing relationship with different portions of the duplicating pad.

14. A flat bed duplicating machine, comprising in combination a frame, a bed mounted on said frame and provided with means for holding a duplicating pad in position thereon, a carriage movable along said bed longitudinally of the machine, a tray on said carriage for supporting a copy sheet, means for forcing the copy sheet at a predetermined point on the tray into printing relationship with said duplicating pad, a circular rod mounted on said carriage longitudinally of the machine a short distance above said tray and having a series of notches therein in spaced relation therealong, a slide block slidably mounted on said rod, an elastic clutch member carried by said slide block adapted by yielding engagement with one of said notches to hold the slide block in predetermined adjusted position on the rod but adapted to yield for the adjustment of said slide block along said rod, a margin bar movably connected with said slide block so as to rest in transverse position on said tray, a second slide bar on said carriage adapted by sliding engagement with a notch in said slide block to hold said block in normal operative position, and means for giving said carriage successive step movements along said bed for bringing copy sheets into printing relationship with different portions of the duplicating pad.

15. A flat bed duplicating machine, comprising in combination a frame, a bed mounted on said frame and provided with means for holding a duplicating pad in position thereon, a carriage movable along said bed longitudinally of the machine, a tray on said carriage for supporting a copy sheet, means for forcing the copy sheet at a predetermined point on the tray into printing relationship with said duplicating pad, a slide bar mounted on said carriage longitudinally thereof a short distance above said tray, a margin bar slidably mounted on said slide bar so as to be held in transverse position a short distance above said tray in any desired adjustment longitudinally of the machine, yielding

means for holding said margin bar releasably in position on said slide bar at any of a series of successive stop positions along the bar, stop means carried by said transverse margin bar so as to be adjustable transversely of the machine thereon, means for releasably securing said stop means in adjusted position on the margin bar, and means for giving said carriage successive step movements along said bed for bringing copy sheets into printing relationship with different portions of the duplicating pad.

16. A flat bed duplicating machine, comprising in combination a frame, a bed mounted on said frame and provided with means for holding a duplicating pad in position thereon, a carriage movable along said bed longitudinally of the machine, a tray on said carriage for supporting a copy sheet, means for forcing the copy sheet at a predetermined point on the tray into printing relationship with said duplicating pad, a slide bar mounted on said carriage longitudinally thereof a short distance above said tray, a margin bar slidably mounted on said slide bar so as to be held in transverse position a short distance above said tray in any desired adjustment longitudinally of the machine, yielding means for holding said margin bar releasably in position on said slide bar at any of a series of successive stop positions along the bar, stop means slidably mounted on opposite end portions of said margin bar so as to be adjustable transversely of the machine thereon and arranged so as to be readily slidable out of engagement with the margin bar, means for releasably securing said stop means in adjusted position on the margin bar, and means for giving said carriage successive step movements along said bed for bringing copy sheets into printing relationship with different portions of the duplicating pad.

17. A flat bed duplicating machine, comprising in combination a frame, a bed mounted on said frame and provided with means for holding a duplicating pad in position thereon, a carriage movable along said bed longitudinally of the machine, a tray member on said carriage for supporting a copy sheet in horizontal position thereon, means for forcing the sheet at a predetermined point on the tray into printing relationship with said duplicating pad, margin bar means for controlling the position of a copy sheet on said tray, means for giving said carriage successive step movements along the bed, an extension tray member, and means for removably connecting said extension tray member with said first-named tray member, comprising pivot pins carried by one of the tray members engaging sockets carried by the other tray member so as to permit said extension tray member to be slid transversely of the machine out of engagement with the other tray member, and a lug on one of said tray members adapted by engagement with the other tray member to prevent disengagement of the tray members when the extension member is in normal lowered position but adapted to stand free of said other tray member when the extension member is swung upwardly on said pivot pins.

HUBERT JAGGER.
